US00D415703S

United States Patent

[19]

Hutton et al.

[11] Patent Number: Des. 415,703

[45] Date of Patent: ** Oct. 26, 1999

[54] MANIFOLD

[76] Inventors: **Peter B. Hutton**, 2024 26 A Street S.W., Calgary, Alberta, Canada, T3E 2C1; **Alan F. Chou**, 907 Venice St., Sugar Land, Tex. 77478; **Jeffrey T. Lynch**, 3822 Senna Pl., Sugar Land, Tex. 77479; **James W. Spahr**, 8511 Concho St., Houston, Tex. 77036

[**] Term: **14 Years**

[21] Appl. No.: **29/080,337**

[22] Filed: **Dec. 4, 1997**

[51] LOC (6) Cl. **10-04**

[52] U.S. Cl. **D10/96**

[58] Field of Search .... D10/96; 73/23.2, 73/405 R, 756; 137/343, 552, 577, 580, 597, 884.1

[57] CLAIM

The ornamental design for a manifold, as shown and described.

DESCRIPTION

FIG. 1 is a perspective view of the front and top of one embodiment of a manifold showing our new design;

FIG. 2 is an elevational, side view of the embodiment of FIG. 1, the other side view being identical;

FIG. 3 is a front, elevational view of the embodiment shown in FIG. 1;

FIG. 4 is a top, plan view of the embodiment shown in FIG. 1;

FIG. 5 is a rear, elevational view of the embodiment shown in FIG. 1;

FIG. 6 is a bottom, plan view of the embodiment shown in FIG. 1;

FIG. 7 is a perspective view of the front and top of another embodiment of a manifold showing our new design;

FIG. 8 is an elevational view of one side of the embodiment shown in FIG. 7, the other side view being identical;

FIG. 9 is a front, elevational view of the embodiment shown in FIG. 7;

FIG. 10 is a top, plan view of the embodiment shown in FIG. 7;

FIG. 11 is a rear, elevational view of the embodiment shown in FIG. 7; and,

FIG. 12 is a bottom, plan view of the embodiment shown in FIG. 7.
